UNITED STATES PATENT OFFICE.

DANIEL F. GONWARE, OF CHICAGO, ILLINOIS.

JOURNAL-BOX WEAR-PLATE.

1,173,660.

Specification of Letters Patent. Patented Feb. 29, 1916.

Application filed August 3, 1914. Serial No. 354,674.

To all whom it may concern:

Be it known that I, DANIEL F. GONWARE, a citizen of the United States, residing at Chicago, in the county of Cook and State of Illinois, have invented a new and useful Improvement in Journal-Box Wear-Plates, of which the following is a specification.

My invention relates particularly to wear-plates for the journal-boxes of locomotives and analogous constructions.

The primary object of my present invention is to provide an improvement upon the construction disclosed in my Patent No. 1,082,943, granted December 30, 1913, with 15 a view of securing greater economy in the use of such a wear-plate.

The invention is particularly applicable where the wheel is located outside the journal-box, as in engines, locomotives, tenders, 20 etc.

The invention is illustrated in its preferred embodiment in the accompanying drawings, in which—

Figure 1 represents a horizontal sectional view of a journal-box equipped with a wear-plate in accordance with my invention, the section being taken as indicated at line 1 of Fig. 2, and the view showing also a locomotive wheel and axle brokenly; Fig. 2, a vertical sectional view of the same; Fig. 3, an outer face view of the improved wear-plate; Fig. 4, a top plan view of the same; Fig. 5, an inner face view of the wear-plate; and Fig. 6, an edge elevational view of the wear- 35 plate.

In the construction illustrated, A represents an engine or locomotive wheel secured to or mounted on the end of an axle A¹; B a journal-box; and C my improved holder 40 and wear-plate removably interposed between the wheel-hub 1 and the journal-box.

The journal-box B, sometimes called the driving-box, is fitted with the usual brass 2, which rests upon the axle, and has the usual 45 cellar 3 adapted to contain lubricant. It is common to removably secure the cellar 3 between the downward extensions 4 of the journal-box, by means of cellar-bolts 5.

The general form of my improved holder 50 and wear-plate is shown in Figs. 3 and 5. The device comprises a flat plate 6 which is

recessed or bifurcated to slip over the axle and which is adapted to afford a facing for the outer end of the journal-box, and a correspondingly recessed annular fillet or wear-member 6^a which is removably secured in a recess or socket 6^b in the outer face of the plate 6.

The outer diameter of the member 6^a is greater than the diameter of the hub 1; and 60 outside the circle of the hub 1 the member 6^a is secured in its socket by rivets 7.

The holder plate 6 and the annular insert or wear-member 6^a are recessed centrally from the lower edge upwardly, as indicated 65 at 8, the recess terminating in a semi-cylindrical upper wall 9 which conforms to the upper half of the axle A¹. The plate 6 is provided at its lateral edges with inturned flanges 10. That is, the flanges 10 are turned 70 away from the wheel. The flanges 10 embrace the lateral flanges 11 with which the journal-box B is provided at its outer end; and the flanges 10 are equipped on their inner faces with flanges or guide-tenons 10^a 75 which engage grooves 12 with which the flanges 11 are provided in their vertical edge portions. Thus, it will be seen that the wear-plate is connected to the journal-box by vertical guides, which enable the wear-plate 80 to be removed by a vertical movement. It is preferred to equip the upper end of the plate 6 with an inturned flange 13, which is equipped with a downturned flange 13^a, which hooks over or engages an upstanding 85 flange 14 with which the upper portion of the outer end of the journal-box is provided. The upper portion of the wear-plate 80 is provided with a recess or receptacle 15 for lubricant. From the bottom of the recess 90 15 extends an inclined passage 16 which registers with a corresponding passage 17 in the upper portion of the wear-member 6^a, the passage or duct 17 opening at the vertical face of the wear-member 6^a, as will be 95 understood from Figs. 2 and 3.

As described, the plate 6 has downward extensions or furcations 18, which flank the axle A¹, and these extensions, together with the flanges 10 may terminate somewhat below the cellar 3 of the journal-box, thus enabling the flanges 10 to be provided at

their lower ends with perforations 19, which receive the outer bolt 5 which is employed to secure the cellar-box 3 to the journal-box. Thus, the outer cellar-bolt 5 may be employed to secure the wear-plate against working upwardly on its guides.

The wear-plate and holder may be of brass, or other material suitable to withstand the wearing action of the hub, due to 10 thrust of the axle; or, if desired, the main holder plate may be of steel, and the insert or wear-member 6^a may be of brass. It will be noted that the outer face of the member 6^a affords a wear-surface which 15 contacts with the inner vertical face of the hub of the wheel. When the member 6^a is worn out, the holder-plate 6 may be removed from the axle without dismemberment of the locomotive or tender, as the 20 case may be. It is unnecessary to drop the axle out of its bearing in order to enable a new wearing surface to be applied to the outer end of the journal-box. In accordance with the present invention, the wear- 25 plate may be removed at will, the worn out insert may be taken out and a new insert 6^a may be applied. Thus, the wear-plates may be used over and over again, simply by renewing the wear-members 6^a from time to 30 time, according to necessity.

In standard practice, railway companies are now subjected to great loss of time and large expense to provide against play between the wheel-hub and journal-box, particularly in locomotive construction where the end thrust is at times enormous and the wearing therefore large.

The present invention not only expedites the work of keeping the locomotive in 40 proper running order so far as this feature is concerned, but it does so at a minimum of expense, inasmuch as the discard of worn out parts is reduced to a negligible quantity.

45 The upper portion of the plate 6 is shown provided with recesses 18^a, which may serve for engagement with a hook or other suitable device, for removing the wear-plate from the journal-box.

50 The foregoing detailed description has been given for clearness of understanding only, and no undue limitation should be understood therefrom, but the appended claims should be construed as broadly as 55 permissible in view of the prior art.

What I regard as new, and desire to secure by Letters Patent, is—

1. A device of the character set forth, comprising a "holder-plate" having its 60 lower edge recessed centrally to accommodate an axle, said plate having extensions depending below the axle and said plate being provided with guides adapted to engage guides with which the outer end-portion

tion of the journal-box is provided, and an 65 annular wear-member detachably secured to the outer face of said holder-plate, the lower portion of said wear-member being recessed to accommodate the axle, thus affording portions flanking the axle. 70

2. A device for the purpose set forth, comprising a holder-plate having its outer surface provided with a socket, a wear-member secured in said socket, the lower portion of the plate and wear-member being recessed centrally from the lower edge of the plate to accommodate an axle, said plate thus having extensions depending below the axle and said plate being provided with lateral flanges equipped on their inner 80 surfaces with guide-tenons adapted to slide in lateral grooves at the outer end-portion of the journal-box. 75

3. A device for the purpose set forth, comprising a holder-plate having lateral 85 flanges projecting from its inner surface and equipped with guide-tenons adapted to slide in lateral grooves at the outer end-portion of a journal-box, said plate having its outer surface provided with an annular 90 recess, and an annular wear-member secured in said recess, said annular wear-member and said plate being recessed vertically at the lower edge of the plate to accommodate the axle and affording exten- 95 sions depending below the axle.

4. The combination with a journal-box, of a vertically slideable holder-plate connected with the outer end thereof and recessed vertically from its lower edge to 100 accommodate the axle, said holder-plate having its outer surface provided with an annular socket, an annular wear-member in 105 said socket having its outer peripheral portion riveted to said holder-plate, said wear-member also recessed vertically in its lower portion to accommodate the axle, the furcations of said holder-plate depending beneath the axle, and a connecting member joining the lower ends of said furcations 110 beneath the axle.

5. A device for the purpose set forth, comprising a holder-plate provided on its inner side with lateral flanges having guide-tenons adapted to engage grooves in the 115 lateral vertical surfaces of the outer end-portion of a journal-box, and a top flange at the upper portion of said plate adapted to overlie a portion of the journal-box and having a downturned flange adapted to engage the rear side of an upstanding flange on the upper portion of the journal-box. 120

6. A device of the character set forth comprising a holder-plate, having its outer surface provided with an annular socket, 125 an annular wear-member secured in said socket, having its outer peripheral portion riveted to said holder-plate, the lower por-

tion of said plate and wear-member being recessed centrally from the lower edge of the plate to accommodate an axle, said plate having extensions extending below the axle, and being provided with vertical guides adapted to engage guides with which the outer end portion of the journal-box is provided.
